US00D509824S

(12) **United States Design Patent** (10) Patent No.: **US D509,824 S**
(45) Date of Patent: **** Sep. 20, 2005**

(54) **ENCLOSURE FOR WIRELESS DEVICE**

(75) Inventors: **William J. Storti**, Haverford, PA (US);
Evan A. Groat, Lansdale, PA (US);
Yucheng Jin, Chalfont, PA (US); **Trent H. Punnett**, San Diego, CA (US)

(73) Assignee: **General Instrument Corporation**,
Horsham, PA (US)

(**) Term: **14 Years**

(21) Appl. No.: **29/210,771**

(22) Filed: **Aug. 5, 2004**

(51) LOC (8) Cl. **14-03**

(52) U.S. Cl. **D14/240**

(57) **CLAIM**

The ornamental design for enclosure for wireless device, as shown and described.

DESCRIPTION

FIG. 1 is a perspective view, from the front and above, of an enclosure for wireless device showing our new design.

FIG. 2 is a top view thereof.

FIG. 3 is a bottom view thereof.

FIG. 4 is a left view thereof.

FIG. 5 is a right side view thereof.

FIG. 6 is a front view thereof; and,

FIG. 7 is a rear view thereof.

The broken lines shown in FIGS. 1-7 represent environmental subject matter and form no part of the claimed design.
